UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAYBOLT STRUCTURE.

1,364,186.

Specification of Letters Patent.

Patented Jan. 4, 1921.

Application filed January 20, 1920. Serial No. 352,696.

To all whom it may concern:

Be it known that I, ETHAN I. DODDS, a citizen of the United States, and a resident of Pittsburgh, in the county of Allegheny 5 and State of Pennsylvania, have invented certain new and useful Improvements in Staybolt Structures; and I do hereby declare the following to be a full, clear, and exact description of the invention, such as will enable others skilled in the art to which it 10 pertains to make and use the same.

This invention relates to improvements in staybolt structures for boilers,—one object of the invention being to provide a structure 15 comprising separable members and in which a threaded bearing member may be employed and so mounted in the boiler sheet or connected therewith as to provide a universally adjustable mounting whereby proper 20 alinement of the staybolt with its points of connection with the respective boiler sheets shall be insured and so that the structure shall be rigidly united to the boiler sheet after proper adjustment shall have been 25 effected.

With this and other objects in view, the invention consists in certain novel features of construction and combinations of parts as hereinafter set forth and pointed out in 30 the claims.

In the accompanying drawings, Figure 1 is a sectional view partly in elevation illustrating an embodiment of my invention; Fig. 2 is a view showing the bearing member 35 so mounted in the boiler sheet as to project beyond the same and provided with a plug closure, and Figs. 3 to 11 are views showing modifications.

1 represents an outer boiler sheet and 2 40 the inner sheet of a boiler,—with which latter the inner end of a staybolt 3 may be secured in any suitable manner and the outer end of said staybolt is provided with a head 4 which is connected with the outer boiler 45 sheet by means of devices hereinafter described:

The outer boiler sheet is provided with an opening, a portion of the wall of which is 50 rounded to form a seat 5 for the rounded peripheral portion 6 of a bearing ring 7. The inner end portion of the bearing ring 7 is threaded as at 8 to receive the exteriorly

threaded portion 9 of a bearing member 10. The outer end portion of the bearing ring 7 is threaded interiorly as at 11 for the reception of a plug closure 12 and the latter is provided with an angular portion 13 for the reception of a wrench,—the outer end of said plug closure 12 and its angular portion 13 lying flush with the outer end of the bearing ring 7 and, when the structure is employed as a flush mounting, with the outer face of the boiler sheet. The bearing ring 7 is provided interiorly, between the threaded portions, with an annular flange 14 which lies between the bearing member 10 and the closure 12. The upper end of the closure may abut against the under face of the flange 14 and a gasket 15 will preferably be interposed between the upper face of said flange and the under face of the closure 12. It will be observed that as the bearing ring has a universally movable mounting in the boiler sheet, the bearing member may be adjusted to insure proper alinement of 70 the staybolt with its points of connection with the respective boiler sheets and when such adjustment shall have been effected, the bearing ring will be united to the boiler sheet by means of a weld 16 which occupies 80 a groove formed by a beveled portion 17 of the wall in the boiler sheet and a portion of said ring.

The bearing member 10 is provided interiorly with a seat 18 for the head of the 85 staybolt and a portion of the interior of said bearing member is threaded as at 19 so that when said bearing member is mounted in the boiler sheet with a portion projecting beyond the outer face of the same as shown 90 in Fig. 2, a plug closure 20 having an angular head 21 may be screwed into said bearing member.

When it is desired to use the mounting solely as a "flush" structure, the internal 95 threading 19 of the bearing member may be omitted as shown in Fig. 3.

It will be observed that the rounded portion of the bearing ring and bearing member are struck from different centers but 100 they may be struck from the same center so that the curvature of one will aline with the curvature of the other as shown in Fig. 4, and if desired a gasket 22 may be inter-

posed between the outer end of the bearing member 10 and the under face of the flange 14 in the bearing ring 7.

In Figs. 1, 3 and 4 the bearing ring is 5 united to the boiler sheet by the weld 16, but when the bearing member 10 is mounted as shown in Fig. 2, a weld 23 surrounding said bearing member unites the latter with the outer face of the boiler sheet.

10 In the embodiment of the invention shown in Figs. 5 and 6, 1^a represents an outer boiler sheet and 2^a the inner boiler sheet,—with which latter a staybolt 3^a is connected in any suitable manner and the 15 outer end of said staybolt is provided with a head 4^a which is connected with the boiler sheet by means of the devices hereinafter described.

15 In Fig. 5, wherein the device is shown 20 as a "flush" structure, the boiler sheet 1^a is provided with an opening, a portion of the wall of which is rounded to provide a seat 5^a and another portion of said wall may be made flaring as at 6^a.

25 A sleeve 7^a is adapted for universally 30 movable mounting in the opening in the outer boiler sheet and this sleeve is formed exteriorly with rounded faces 8^a and 9^a, the former of which has universally movable mounting on the rounded seat 5^a in the boiler sheet when said sleeve is so mounted that its outer end is flush with the outer face of the boiler sheet 1 as shown in Fig. 5. The sleeve 7^a is threaded interiorly as at 10^a 35 and at the outer end of this threaded portion a shoulder 11^a is formed and the outer portion of the opening in the sleeve is somewhat greater in diameter than is the threaded portion.

40 A bearing ring 12^a is threaded into the inner end portion of the sleeve 7^a and is provided interiorly with a rounded seat 13^a on which the head of the staybolt has its bearing, and the inner end portion of the 45 opening in the bearing ring may be made flaring as shown at 14^a to permit the "swing" of the staybolt. By thus providing a bearing ring which is threaded into the inner end portion of the sleeve 7^a, the bearing for the head of the staybolt may be adjusted and by mounting the sleeve 7^a in the boiler sheet so that it may be universally movable, a proper alinement of the staybolt with its points of connection with the 55 respective boiler sheets will be insured.

45 A closure 15^a having a threaded exterior portion is screwed into the threaded portion of the sleeve 7^a and is provided with an annular flange 16^a which co-operates 60 with the shoulder 11^a to limit the inward movement of said closure. The closure 15^a is recessed to form a clearance space 17^a for the head of the staybolt and said closure is provided with an angular portion 18^a 65 to receive a wrench,—said angular por-

tion lying flush or substantially so with the outer end of the sleeve 7^a. The peripheral portion at one end of the sleeve 7^a forms, with the beveled portion 6 of the wall of the opening in the boiler sheet, a groove in 70 which a weld 19^a is located to fixedly unite the sleeve 7^a to the boiler sheet.

When it is desired to so mount the device that it will project beyond the outer 75 boiler sheet 1^a, the rounded inner end portion 9^a of the sleeve 7^a will be mounted on a rounded wall 20^a of the opening 21^a in the boiler sheet, as shown in Fig. 6, and the sleeve will be united to the outer boiler sheet by means of a weld 22^a which surrounds said sleeve approximately at the juncture of its rounded portions 8^a and 9^a.

80 In the embodiment of the invention shown in Figs. 7 to 11, 1^b represents an outer boiler sheet and 2^b the inner sheet 85 of the boiler,—with which latter the inner end of a staybolt 3^b is connected in any suitable manner and the outer end of said staybolt is provided with a head 4^b which is connected with the outer boiler sheet as 90 hereinafter described.

95 In Fig. 7 the boiler sheet is shown provided with an opening having a portion of its wall rounded to form a seat 5^b and another portion of said wall may be beveled or flaring as at 6^b.

100 A ring 7^b is located (in Fig. 7) within the opening in the boiler sheet and is rounded exteriorly so as to have universally movable mounting on the rounded seat 5^b in the boiler sheet. The outer end portion of the ring 7^b has greater diameter than the inner end portion interiorly of the ring and both of these portions of the ring are threaded 105 interiorly as at 8^b and 9^b. By thus making the ring with different diameters interiorly, a shoulder 10^b is formed. A bearing member 11^b having a rounded exterior portion 12^b struck from the same center as the rounded exterior portion of the ring 7^b, is 110 provided with an externally threaded shank or extension 12^b which is screwed into the inner end portion of the ring 7^b and between a shoulder 13^b formed on said bearing member and the inner end of the ring, a 115 gasket 14^b is interposed. The bearing member 11^b is provided interiorly with a rounded seat 15^b for the head 4^b of the staybolt.

120 A closure 16^b having peripheral screw threads is inserted into the outer end portion of the ring 7^b and meshes with the threads 8^b therein and between said closure and the shoulder 10^b in the ring 7^b and the outer end of the extension 12^b of the bearing member 11^b, a gasket 17^b may be interposed. The closure 16^b may be made convex so as to provide a clearance space 18^b for the bolt head and said closure may be provided with ribs 19^b to facilitate the application of 125 a wrench.

After the mounting has been adjusted to insure proper alinement of the bolt with its points of connection with the respective boiler sheets, the ring 7^b may be united to the boiler sheet by a weld 20^b which occupies a groove formed by the beveled portion 6^b of the wall of the opening in the boiler sheet and a portion of the ring 7^b.

If desired the opening in the boiler sheet 10 1^b may have its wall rounded approximately from the outer to the inner face of the sheet and the mounting may be seated in the opening so as to be universally movable on such wall, as shown in Fig. 8. In this instance, 15 the ring 7^b projects a comparatively short distance beyond the outer face of the outer boiler sheet and both the ring 7^b and the bearing member 11^b are mounted on a rounded seat in the boiler sheet. When thus 20 mounted the ring will be united to the boiler sheet by a weld 21^b surrounding said ring.

In the construction shown in Fig. 9 the wall of the opening in the boiler sheet is 25 made with a comparatively shallow rounded wall 22^b on which the rounded portion of the bearing member only has universal mounting. When the device is thus mounted it will, after having been adjusted, be 30 united to the boiler sheet 1^b by a weld 23^b which surrounds the inner end portion of the ring 7^b and also a portion of the bearing member 11^b.

Instead of providing a ring 7^b having two 35 different inside diameters as shown in Figs. 7, 8 and 9, the ring may have a uniform inside diameter throughout as shown in Fig. 10.

In the construction shown in Fig. 11, the 40 external rounded portions of the ring 7^b and the bearing member 11^b are struck from different centers, instead of both being struck from the same center, as shown in Figs. 7, 8 and 9.

Having fully described my invention 45 what I claim as new and desire to secure by Letters-Patent, is:—

1. In a staybolt structure, the combination with a boiler sheet having an opening, a bearing device having two portions, each 50 portion having a rounded exterior and either of said rounded portions adapted to seat against the boiler sheet at the opening therein, a seat in one portion of the bearing device, a staybolt having a head mounted 55 on said seat, and a removable closure for said bearing member over the head of the staybolt therein.

2. A mounting for the head of a staybolt comprising a bearing ring having a 60 rounded exterior and having an internal annular flange, said bearing ring having threaded portions at respective sides of said flange, a bearing member for the head of a staybolt screwed into said bearing ring, and 65 a closure screwed into said bearing ring at the other side of said flange, said flange being interposed between said bearing member and closure.

3. In a staybolt structure, the combination with a boiler sheet having an opening therein, of a bearing ring having an initially universally movable mounting in said opening, said bearing ring having internal screw threads near respective ends, a bearing member threaded externally and internally and entering said bearing ring, a threaded closure entering said bearing ring, said bearing ring having an internal annular flange interposed between said bearing 75 member and closure, a weld uniting said bearing ring to the boiler sheet, and a staybolt having a head mounted in said bearing member.

In testimony whereof I have signed this 80 specification.

ETHAN I. DODDS.
